Primary Examiner—Jeffrey Asch
Attorney, Agent, or Firm—Christie, Parker & Hale, LLP**[57] CLAIM**

The ornamental design for ear cushion for telephones, as shown and described.

DESCRIPTION

FIG. 1 is a top plan view of an ear cushion for telephones showing my new design;

FIG. 2 is a cross-section view of the cushion as taken along line 2—2 in FIG. 1;

FIG. 3 is a cross-section view of the cushion as taken along line 3—3 of FIG. 1;

FIG. 4 is a bottom end elevation view of the cushion, a top end elevation view being a mirror image of FIG. 4; and,

FIG. 5 is a left side elevation view of the cushion, a right side elevation view being a mirror image of FIG. 5;

The bottom plan view of the cushion is the same in appearance as the FIG. 1 with the addition of an additional concentric recess as shown by the content of FIGS. 2 and 3 and, without the rounded outer edge.
